UNITED STATES PATENT OFFICE.

GEORGE J. QUALMAN, OF TOLEDO, OHIO.

HAIR DRIER.

Application filed December 16, 1920. Serial No. 431,310.

To all whom it may concern:

Be it known that I, GEORGE J. QUALMAN, of Toledo, Lucas County, Ohio, have invented certain new and useful Improvements in Hair Driers, of which the following is a full, clear, and exact description, such as will enable others skilled in the art to which it appertains to make and use the same, reference being had to the accompanying drawings, and to the reference characters marked thereon, which form a part of this specification.

In devices for drying the hairs of women after shampoos, the chief objection,—one which precludes their general adoption,—is the expense of such devices owing to their complication and the number of parts involved in their construction, including blowing fans and various kinds of heating devices. The purpose of the present invention is to largely obviate the difficulty here indicated, and, more particularly, to furnish a hair drying device which shall be exceedingly cheap and simple and by means of which an ordinary vacuum cleaner and a common cook-stove may be utilized to furnish a regulated current or blast of warmed or heated air for hair drying purposes.

The inventive idea here outlined may find expression in a variety of forms. One illustrative embodiment of a device for attaining the advantages referred to, which I find efficient in practice, is illustrated in the accompanying drawings, in which,—

35 Figure 1 is a top plan-view of my device; Fig. 2, a side-elevation of the same, and Fig. 3, a sectional elevation taken on a vertical line through the regulating valve hereinafter referred to.

40 Like reference-characters represent like parts throughout the drawings.

While in the operation of my device a blower and a heater are indispensable, they are not indicated in the drawings, for the 45 reason that any flat topped stove will answer for the heater element, and any vacuum cleaner will serve as the blower, these structures in their various forms being well understood.

50 In the drawings, 1 is a vertical tubular member, open at top and bottom, composed preferably of sheet metal, and, in the present illustrative device, cylindrical in cross-section. 2 is a horizontal tubular member one 55 end of which projects through a closely fitting opening into the part 1 near its bottom,

This end of the part 2 is closed except for an upwardly turned opening 13. The opposite end of the part 2 is adapted for connection, through the usual vacuum cleaner 60 hose or otherwise, to the blower side of a vacuum cleaner. 4 is a butterfly-valve, secured to a stem 5, and at 6, which stem extends through the part 2. A spring 7, interposed between the part 2 and the handle 65 8, on one end of the stem 5, presses the stop 9, secured to the other end of the stem, against the part 2, so that the valve is frictionally held at any point to which it may be turned.

70 Assuming that the opening 11 is connected with the air-discharge of a vacuum cleaner, as above indicated, and that the lower end of the part 1 rests upon or as close to the top of a heated stove as may be desired. 75 Now, when the fan of the vacuum cleaner is in motion, there will be a current of air through the members 1 and 2, from inlet 11 to outlet 12, as indicated by the arrows, the strength of such current being determined by the adjustment of the valve 4. The current caused by the fan causes an induced current through the part 1 from its bottom 3 to the outlet 12, the combined currents delivering a considerable volume of 80 warmed or heated air, which when directed through wet tresses, rapidly dries them.

Having described my invention, what I claim and desire to secure by Letters Patent of the United States, is,—

90 1. A device of the described character, comprising an upright tubular member open at top and bottom and adapted to rest upon a stove-top, a horizontal tubular member one end of which projects into and discharges 95 upwardly in the first mentioned member, the other end being adapted for connection with the discharge opening of an air supply, and a valve in said horizontal member.

2. A structure as specified in claim 1, in 100 combination with spring-controlled means for frictionally holding said valve in adjusted position.

3. In a hair drier, a tubular member, and a chamber into which the member projects 105 with a discharge opening on one side and adapted to receive heated air from a stove at the opposite side of said member entrance to the chamber, said member being provided with an opening which may be placed in 110 communication with the blower side of a source of air supply whereby the current

from the air supply causes a current of mixed heated air and cool air through said chamber.

4. A hair drier embodying a chamber open to a heated air supply, and a branch tubular member to said chamber, said member being open away from the heated air supply to direct air flow from the heated member directly away from the heated air

supply for drawing the heated air supply 10 for flow through the chamber as impelled by said flow from the tubular member.

In testimony whereof, I affix my signature in presence of two witnesses.

GEORGE J. QUALMAN.
